DESIGN FOR A BROOCH OR SIMILAR ARTICLE

John Montaquila and Samuel Montaquila,
Cranston, R. I.

Application September 6, 1946, Serial No. 133,098

Term of patent 3½ years

(Cl. D45—19)

To all whom it may concern:

Be it known that we, John Montaquila and Samuel Montaquila, citizens of the United States of America, residing at Cranston, in the county of Providence and State of Rhode Island, have invented a new, original, and ornamental Design for a Brooch or Similar Article, of which the following is a specification, reference being had to the accompanying drawing, forming part thereof.

Fig. 1 is a top plan view of a brooch embodying our new design with the fastener element thereof shown in broken lines, and

Fig. 2 is a side elevational view of the brooch as shown in Fig. 1.

We claim:

The ornamental design for a brooch or similar article, substantially as shown.

JOHN MONTAQUILA.
SAMUEL MONTAQUILA.
